H. JACOVITZ

CUTTER ATTACHMENT FOR SEWING MACHINES

Filed July 1, 1925

UNITED STATES PATENT OFFICE.

HARRY JACOVITZ, OF NEW YORK, N. Y.

CUTTER ATTACHMENT FOR SEWING MACHINES.

Application filed July 1, 1925. Serial No. 40,729.

My invention relates to cutter attachments for the picot edge stitching sewing machines and has reference more particularly to a rotary knife located at the presser foot and operated from the fly-wheel of the sewing machine.

Another object of the invention is to provide a cutter attachment which can be raised independently of the presser foot or there-
10 with.

Another object of the invention is to pro-
15 vide a cutter attachment which can be easi-
ly thrown into or out of operative engage-
ment without reducing the speed of the ma-
chine.

In the appended drawing forming part
20 of this application, Figure 1 is a rear ele-
vation of a sewing machine provided with
an embodiment of my invention. In this
figure the attachment is illustrated in full
lines, while the sewing machine proper, parts
of which do not enter in the combination
with my attachment, are shown in broken
lines.

Figure 2 is an end elevation of the sewing
25 machine, the cutter attachment being shown
in solid lines with the parts entering there-
to in combination, while the other part of
the sewing machine is shown in broken lines.

Figure 3 is a vertical section through the
30 cutter attachment on line 3/3, Figure 5.
Figure 4 is a section on line 4/4, Figure 5,
the cutter attachment in this figure being
shown in a raised or non-operative position,
35 and Figure 5 is an elevation of the cutter
attachment in direction of arrow 5 as shown
in Figure 1.

Referring to the drawing, 10 is a rotary
35 knife mounted to rotate with a shaft 11 to
which is keyed a gear 12. Shaft 11 is ro-
tatively mounted in a bearing 13 of a car-
riage 14. Said carriage 14 is movable on the
presser foot body 15 through the medium of
40 slots engaged by screws 16.

To make the structure more rigid at the
45 presser foot, a spacer plate 17 is interposed
between the carriage 14 and the presser foot
body 15. This plate 17 is secured firmly to
the presser foot body. In the carriage, 14, is
50 revolvably mounted a shaft 18 to which are
pinned a gear 19 and a bevel pinion 20. The
motion from the gear 19 to the gear 12 is
transmitted by an idler gear 21, also mount-
ed on the carriage 14. Therefore, the cut-
55 ter 10 gears 12, 21 and 19 and also the bevel

pinion 20 will move bodily with the car-
riage 14 when the same is moved.

The movement of the carriage is con-
trolled by a latch pin 22, which engages the
60 plate 17 in either of the holes 23, 24, accord-
ing to whether the cutter is in inoperative
or in operative position. See Figures 3 and
4, respectively. The latch pin is actuated by
a bell crank lever 25, the spring 26 of which
65 normally tends to move the pin 22 into en-
gagement with the plate 17. A thumb piece
27 is provided on the carriage 14 to co-oper-
ate with the bell crank lever 25.

The presser foot body 15 is secured in an
70 ordinary way to a tubular presser foot bar
28. The tubular presser foot bar is operated
in the ordinary way, that is to say, when it is
raised, the presser foot is raised from the
75 platen of the machine. Revolvably mount-
ed in the tubular presser foot bar 28 is a
shaft 29. The lower end of the shaft 29
carries a bevel gear 30 constrained to re-
80 volve with the shaft and which gear 30 is
preferably made to bear in the lower part of
the presser foot body 15. The bevel gear
85 30 meshes with the bevel pinion 20 when the
rotary cutter 10 is in operative position, as
shown in Figure 3, but when the rotary cut-
ter 10 is placed into inoperative position, the
pinion 20 is raised out of engagement from
90 the bevel gear 30. See Figure 4.

The upper end of the shaft 29 also carries
a bevel pinion 31, which is in mesh with a
bevel gear 32, to which gear 32 motion is
transmitted through a shaft 33 and a wheel
34 bearing on the fly-wheel 35 of the sewing
95 machine. Suitable bearings 36 are provided
for the shaft 33 on the machine. When the
tubular presser bar 28 is raised it carries
therewith the shaft 29 through the medium
of a collar 37 and thereby disengages the
bevel pinion 31 from the bevel gear 32.

To obtain the desired cutting effect from
the cutter 10, the platen 38 is provided with
100 a slit to accommodate the edge of the cutter
when the same is in operative position. As
already noted, the entire mechanism is lo-
cated on the inner side of the presser foot
body and is flat against it, so that it will not
105 interfere with the fabric being worked on,
and which permits an easy access to any part
of the attachment and in no way interferes
with any part of the mechanism of the
sewing machine.

From the above description it will be seen 110

that the bevel gear 30 with the bevel pinion 20 forms the coupling means for the cutter 10 to the shaft 29, and this coupling means is controlled by the movement of the cutter 5 10 to and from the platen 38. In the same light, the bevel pinion 31 and the bevel gear 32 constitute the coupling means for the shaft 29 from the shaft 33, and the movement of the presser bar 28 to and from the 10 platen also controls the coupling of said gears 31 and 32.

I claim:

1. A cutter attachment for sewing machines comprising in combination a tubular 15 presser bar, a cutter carried by the bar and means for transmitting motion from the sewing machine to the cutter through the tubular bar.

2. A cutter attachment for sewing machines comprising in combination a tubular 20 presser bar, a circular cutter carried by the bar, and motion transmission means from the machine to the cutter through the tubular bar.

3. A cutter attachment for sewing machines comprising in combination a tubular 25 presser bar, a shaft revolvably mounted in said tubular bar, a circular cutter carried by the bar, means for coupling and uncoupling 30 said cutter to the shaft, and motion transmission means from the machine to the shaft.

4. A cutter attachment for sewing machines comprising in combination a tubular

presser bar, a shaft revolvably mounted in 35 the bar, a circular cutter carried by the bar, motion transmission means from the shaft to the cutter, means for coupling and uncoupling the motion transmission means to the cutter and motion transmission means 40 from the machine to said shaft.

5. A cutter attachment for sewing machines comprising in combination a tubular 45 presser bar, a shaft revolvably mounted therein and adapted to participate in the longitudinal movement of said bar, motion transmission means from the machine to the shaft, a circular cutter on the said bar, a train of gears for rotating said cutter and coupling means interposed between said 50 shaft and train of gears.

6. A cutter attachment for sewing machines comprising in combination a tubular 55 presser bar, a shaft revolvably mounted in said bar and adapted to participate in the longitudinal displacement of said bar, motion transmission means from the machine to the shaft for revolving the same, a carriage on said bar, a circular cutter revolvably mounted in the carriage, a gear carried by said shaft 60 and a gear carried by said carriage, means for moving said carriage, in pre-determined positions whereby the two gears may be coupled or uncoupled, and motion transmission means from said gear of the carriage to 65 the cutter thereon.

HARRY JACOVITZ.
